UNITED STATES PATENT OFFICE

EDWIN C. KENTON, OF GREAT NECK, NEW YORK, ASSIGNOR TO H. R. MALLINSON & CO., INC., OF NEW YORK, N. Y., A CORPORATION OF DELAWARE

DESIGN FOR A TEXTILE FABRIC OR SIMILAR ARTICLE OF MANUFACTURE

Application filed December 13, 1929. Serial No. 33,783. Term of patent 3½ years.

To all whom it may concern:

Be it known that I, EDWIN C. KENTON, a citizen of the United States of America, residing at Ravine Road, Great Neck, in the county of Nassau and State of New York, have invented a new, original, and ornamental Design for Textile Fabric or Similar Article of Manufacture, of which the following is a specification, reference being had to the accompanying drawing, forming a part thereof, and showing a face view of a piece of textile fabric embodying my design, the shading indicating contrast in color. A repeat unit is contained within the lines A—A and B—B, which unit is repeated over the surface of the fabric in the relation shown.

I claim:

The ornamental design for a textile fabric or similar article of manufacture substantially as shown and described.

EDWIN C. KENTON.
